UNITED STATES PATENT OFFICE

JOSEPH N. LAGASSE, OF UPPER DARBY, PENNSYLVANIA

HAIR DRESSING DEVICE

Application filed June 18, 1931. Serial No. 545,169.

My invention relates to the so-called method of "permanent" waving of the hair upon a person's head and pertains especially to the clamping and winding of the hair upon 5 forms preparatory to treating with heat in order to set the hair in a wave or curl.

One purpose of my invention is to provide a quick and positive fastening means whereby predetermined portions of the hair can be 10 made fast to a form or rod.

A further purpose is to provide a form or rod having a fastening device therein and which permits quick attachment or detachment of the hair very close to the scalp with 15 a minimum of discomfort to the person about to be treated.

A further purpose is to provide mechanism which will permit the operator to apply it at any point outward of the scalp, and which 20 will prevent the breaking or cutting of the hair.

A further purpose is to provide a winding device which is adapted to operate upon the form or rod, and to fasten upon the rod at 25 any position throughout its length of travel.

A further purpose is to provide a winding device which may be used by either right-handed or left-handed operators.

A further purpose is to provide a winding 30 device which will hold the hair tight upon the rod at any point throughout its path of travel.

A further purpose is to provide a winder which combs and straightens the hair as it 35 winds it.

A further purpose is to provide a winding device which is equally efficient in its operation upon short, medium or long hair and 40 can be released at any point upon the rod and still hold all of the individual hairs securely.

Further purposes will appear in the specification and in the claims.

I have elected to show one only of the many forms in which my invention could be made, selecting however a form that is practical and efficient in operation and which well illustrates the principles involved.

Figure 1 is a plan view of a form or rod

for curling hair, actual size, and embodying several features of my invention.

Figure 2 is a central horizontal section thereof, on a greatly enlarged scale.

Figure 3 is a central horizontal section 55 taken on the line 3-3 of Figure 1 and corresponding in scale to Figure 2.

Figure 4 is a view similar to Figure 1 showing the rod attached to a lock of hair, a winding attachment in place and several 60 turns of hair having been made upon the rod.

Figure 5 is a view similar to Figure 4 showing the completion of the wrapping or 65 curling of the hair upon the rod.

Figure 6 is a perspective view of the winding attachment.

Figure 7 is a similar view taken from a different angle.

Figure 8 is an enlarged detail plan of the 70 tip end of the rod.

Figure 9 is an end elevation thereof.

Figure 10 is a view of the opposite end of the rod to that shown in Figure 9.

Figure 11 is a transverse section taken on 75 the line 11-11 of Figure 2.

Figure 12 is a similar section taken on the line 12-12 of Figure 3.

Figure 13 is a view of a head with a plurality of rods and winders attached.

Figure 14 is an enlarged end elevation of 80 a winder.

Figure 15 is a similar view of the opposite end to that shown in Figure 14.

Like numerals refer to like part in all 85 figures.

Describing in illustration and not in limitation and referring to the drawings:—

In this art it is the custom first to fasten selected portions of the hair to a forming 90 or curling rod, to wrap the hair about the rod and to retain the hair in its wrapped position preparatory to its being subjected to a machine for heat treating.

In the past it has been customary to use 95 rods having enlarged end fastening devices for the initial attachment of the hair to the rod, or to tie the hair to the rod with strings. When it is realized that as many as twenty-four to forty-eight rods may be used simul- 100

taneously, it will be appreciated that weight is an important factor, and the extra weight of the enlarged end fastening devices has always been objectionable.

5 A further objection has been the position which the fasteners necessarily must occupy next to the head. The area of the face of these fasteners is considerable and with the rods extending outward from the centers of the fasteners an excessive pressure is set up 10 by the lower edge of each fastener against the head.

15 In order to overcome the pressure of the fasteners and also their weight, the next step in the art was to provide the ends of the rods with slots into which strings were inserted, and the strings were then carried around selected portions of hair and tied by the 20 hands of the operator.

25 Tied fastenings are objectionable because of the length of time consumed in tying, the discomfort caused the patron (both during tying and untying); the breaking of the hair at the point where tied, and the fact that the head is covered with a multiplicity of dangling strings during the heating operation which may come in contact with the heaters, scorch and probably ignite, causing serious damage.

30 It has been my aim in the present invention to overcome all of these objections and at the same time provide a device which will be more efficient in the production and retention of a much better wrap or curl prior 35 to the application of the heat-treating device.

36 The form or rod is indicated at 20, and carries at one end a specially shaped tip 21 and at its opposite end a separate handle portion 22 knurled upon its outer exposed surface and rotatable upon the rod.

40 A double strand of flexible stranded wire 23 passes through the center of the rod 20, emerging in a loop 24 at the tip end 21 of the rod, and ends in a ball-shaped terminal 45 25.

46 A locking device 26 which operates upon the wire 23 is carried in the knurled handle portion 22, and consists of a hollow body 27, and a hollow plunger element 28 surrounding the flexible stranded wires 23. The locking device is continuously pressed to closure by the action of a spring 29.

51 The inner end of the hollow plunger 28 is tapered as at 30, corresponding to a somewhat similar taper 31 formed at the inner end of the hollow body 27. Carried in openings in the tapered portion 30 of the plunger 28 are a pair of balls 32 which bear against the taper 31 at one point, and upon the two strands of the flexible wire 23 at another, and they are held in continuous contact therewith by the action of the spring 29. This construction permits the ball element 25 to be moved 60 65 away from the body 20 (thereby shortening

the loop 24) and at the same time prevents movement of the wire in the reverse direction unless the locking device 27 be released.

6 A To release the locking action of the balls 32, the hollow plunger 28 is pulled back 70 against the action of spring 29, thereby drawing the balls 32 from contact with the taper surface 31 of the body of the locking device 27 and permitting the wires 23 to slide freely between the balls. To enable the operator to 75 manipulate this release with ease, I provide an enlarged head 33 at the outer end of the hollow plunger 28. The structure of this portion of my device is best seen by referring to Figures 2, 3 and 12.

80 The foregoing structure is but one of several possible means for locking and releasing the semi-flexible member within the forming rod, and I desire to cover such in the appended claims within reasonable scope of the 85 showing here made.

86 Referring now to Figures 2, 3, 8 and 9, it will be observed the tip 21 is formed in such manner as to hold a bunch of hair within its contours and to permit the loop 24 to be 90 drawn in close upon the bunched hair with a minimum of tendency to cut or break the hair.

95 The extreme free end of the tip is concaved on its upper face as at 34, and a further concavity 35 is located toward the rear of the tip. Midway between these two concavities are openings 36 for the reception of the wires 23, and these wires travel over a level portion 37, between the two concaved portions 34 and 35 during their entrance and egress 100 to and from the openings 36. The openings 36 start near the inner end of the tip adjacent one another and gradually diverge from one another toward their outer ends, forming in effect a V when viewed in plan and as illustrated in Figures 2 and 8. The object of these V-shaped openings is to start the travel of the wires 23 away from each other to facilitate the opening of the loop 24 as the wires 23 are moved forward.

105 The body portion 20 is tubular and contains a second tube member 38 threaded at one end within an opening at the inner end of the tip portion 21, and fastened at its opposite end to the knurled handle portion 22. Any 110 rotary movement upon the handle portion 22 will be transferred to the tube 38, and in turn to the tip portion 21, causing the tip to turn with the handle 22. The tube 38 also houses the wires 23 during their passage through the outer body portion 20 from the tip 21 to the handle portion 22, and through the handle portion to a point where it adjoins the body of the locking device 27.

115 The knurled handle 22 is rotatable upon the body 20 in one direction only, because of an interposed spring clutch 39 within the body 20 and surrounding a reduced extended portion 40 of the handle 22. One end of this 120 spring is held within the reduced portion 40, 130

while the opposite end is free. The spring fits snugly between the extended portion 40 and the inside walls of the hollow body 20. As shown in the drawings (Figures 2, 3 and 11) if the knurled handle 22 is turned in a clockwise direction, the convolutions of the spring will tighten upon the tube 38, and slip within the body 20, permitting the handle 22 and therewith the tip end 21 to turn while the body 20 is held stationary. If the handle 22 be rotated in a counterclockwise direction, the spring 39 will expand, its free end 41 (Figure 11) contacting with the inner face of the body portion 20, and turning the body with the handle 22 and tip 21.

It will be evident that the rod could be made to operate in either direction by reversing the direction of winding of the spring 39 is so desired.

The entire assembly of the component parts of the form just described will not weigh more than the rods or mandrels used prior to my invention, and the ease and speed with which they can be attached to and detached from the hair will cause the patron a minimum of inconvenience.

The winding attachment 45, best seen in Figures 4, 5, 6, 7, 14 and 15, is made of flat spring metal, bent to the shape illustrated, and comprises two separate areas 46 and 47, 46 for engaging the rod proper and 47 for engaging the hair and pressing it to the rod.

The area 46 comprises a flat strip portion spirally wound and having a spring finger 48 at one end and a spring finger 49 at the opposite end of the area. The finger 48 is designed to receive the longitudinal pressure of a bunch of hair as it is wound upon the rod, while the finger 49 exerts pressure upon the rod 20. The outer face of this area is knurled to prevent the slipping of the fingers when the winder is held by the operator.

The area 47 comprises a hook finger 50 extending from the body portion in one direction, and a series of smaller fingers 51 extending from the body portion in the opposite direction. At the base of the hook finger 50 or at the point where it leaves the body portion, and to one side thereof, I provide an enlarged opening 52, for the reception and retention of a lock of hair. (See Figures 4-6 and 7.) Fingers 51 are in effect the teeth of a comb, and as they spiral during winding, they fold under and pack the minute short ends of hair making a perfectly tight wind free from small protruding hairs.

The effect of the fingers 51 is heightened and changed by the fact that each individual comb tooth separately resiliently presses and strokes as the winding proceeds. As a result of this, the fingers not only independently adapt themselves to the variant thicknesses of the coil under the different fingers but they press down beneath the surface 65 where the hair on the surface of the coil is in

the least loose and straighten the hair, giving a combing effect which nevertheless rides over tangles. This gives a considerable part of the beneficial effect of normal combing without the injury which would result from tearing out the tangles if the comb were positive in its action instead of resilient and of a stroking character. Though there would be some advantage in this with comparatively wide terminals to the spring fingers or teeth, 70 the combing advantage is due almost wholly to the fact that the ends of the fingers are narrow and will therefore pass between the individual hairs at the surface and dip down beneath the surface to give the straightening 80 effect sought and not merely a rubbing upon the surface of the coil.

A definite cooperation exists between this combing feature and the mechanism by which reverse movement of the device is prevented; 85 in that the combing fingers or teeth can not dig down deeply into the roll as would be the case if the winding were reversed.

As the fingers effecting the combing operation are resiliently pressed toward the rod 90 or mandrel and may be made to engage the mandrel when no coil is present, no strand of hair is too thin to receive the benefit of the stroking action. Moreover, the enlarged opening 52 of the winder which centers the block or strand at the same time limits the thickness of strand which can be treated at one time. For this reason no strand of hair and no coil formed by it can be too thick to 95 also receive the benefit of the stroking combing action of these fingers 51.

The shape of this member 45 is important and enlarged details (Figures 14 and 15) have been inserted in this application for the purpose of clearly showing the best form 105 known to me, as required by the statute and of illustrating the functions of the various parts.

The finger 49 presses upon the outer face 110 of the rod 20, providing a grip or means of retention even upon the decreased area at the tapered end of the rod. When the finger 49 grips the rod as the wound hair endeavors to unwind within the area 47, the entire spiralled area 46 tightens upon the rod and prevents any back or reverse turning of the winder on the rod.

The finger 48 is for a different purpose. It acts as a stop against which the hair abuts as it is wound, tending to force the winder 120 away from the hair and creating a spiral winding effect of the hair on the rod.

The series of small circumferentially extending spring fingers 51 exert pressure upon the lock of hair as it is wound upon the forming rod 20, and their spring nature makes it possible to keep a constant tension upon the hair, regardless of the size of the lock, at all times throughout its advancement upon the rod. 125 130

In operation selected portions of hair are "blocked off" on the patron's head and the wire loop 24 of the forming rod 20 is placed about one of the selected portions of hair. The operator then draws the terminal 25 outwardly from the rod 20 thereby causing the wire loop 24 to close upon the selected portion of hair. The concavities 34 and 35 at the tip end of the rod permit the hair to retain the round formation of the selected portion, and the wire loop 24 will then lie over the hair in such manner as to prevent breakage which might occur if there were any abrupt edges present.

The wires are free at all time to move outwardly from the free end of the body 20 due to the construction of the wire clamping device 26, and any movement of the wires in the opposite direction is immediately stopped by the action of the balls 32 within the clamping device 26. It will thus be seen that a lock of hair can be drawn in tightly against the tip 21 of the rod 20 and be retained in position by the action of the wire clamping device 26.

The hair is now twisted upon the rod 20 for a desired number of turns, and the remaining free end is caught under the hook finger 50 of the winding attachment 45 and is drawn into the opening 52. The operator now turns the winding attachment 45 upon the rod in the direction of the arrow as indicated in Figures 6 and 7 (if he be a right-handed winder, but if he is a left-handed winder, the winding device is made just the opposite to that shown here, and is turned in the opposite direction). The small fingers 51 engage the hair as it is caught within the winder and press tightly against the rod 20, and the tightened windings of the hair itself bear against the finger 48 camming the winding device laterally of the rod in a spiral movement. At all times throughout this spiral winding the spring finger 49 is in contact with the rod 20 and pressure upon the knurled portion of the winding device within the area 46 will cause the finger 49 to slightly release its tension and permit it to rotate about the rod 20, but as soon as the pressure upon this portion of the winder is released, the spring finger 49 will contact tightly against the rod and prevent any tendency of the winder to reverse. It will thus be seen that the hair can be wound upon the rod for any distance and the winder may be stopped at any point and will retain the hair tightly wound.

A final tightening of the hair upon the rod is made by the operator holding the handle 22 stationary and turning the body portion 20 in the same direction in which he has been winding. As before described this body portion moves free of the tip 21 and the handle 22 in one direction and is prevented from moving in the reverse direction by the action

of the spring 39. This final tightening may be but a fraction of a turn or as much as a half turn, but the loop 24 and tip 21 retain their fixed relation to the lock of hair whatever the amount of the turn in this final tightening operation may be.

This operation is repeated about the head until the desired number of rods have been wound, at which time the rods are inserted in the heat-treating device which is old and well known in this art and forms no part of the present invention.

Upon the completion of the heat treatment the rods are removed from the heating machine, and the locks of hair are successively released from the rods. In order to accomplish this the operator inserts his fingers between the enlarged head 33 of the locking device 27 and the handle portion 22, forcing the enlarged portion 33 outwardly from the handle against the action of the spring 29, thereby causing the balls 32 to release their hold upon the wires 23 and with the locking device in this released position to slide the entire rod member outwardly along the wires, thereby enlarging the loop 24 and permitting the release of the hair. With the hair thus released at the scalp end, its outer free end can be slipped from within the winding device 45 and the entire lock of hair, now in its waved condition, may be removed from the forming rod 20.

The winders 45 in my present invention are left upon the forming rods 20 during the heat treating, thereby eliminating the necessity of the additional wrapping, as is customary in the prior art, with lamb's wool, and the final tying of the wool and hair with additional strings.

In view of my invention and disclosure variations and modifications to meet individual whim or particular need will doubtless become evident to others skilled in the art, to obtain part or all of the benefits of my invention without copying the structure shown, and I, therefore, claim all such in so far as they fall within the reasonable spirit and scope of my invention.

Having thus described my invention, what I claim as new and desire to secure by Letters Patent is:

1. In a device for preforming hair to be curled, a forming rod, a flexible loop, a tie within the rod connecting with the loop at one end, accessible at the other end and a clutch within the forming rod permitting the tie to be moved in one direction and holding it against movement in the opposite direction.

2. In a device for preforming hair to be curled, a forming rod, a flexible loop, a tie within the rod connecting with the loop at one end, accessible at the other end, a clutch within the forming rod permitting the tie to be moved in one direction and preventing

it from movement in the opposite direction, and means for the release of the clutch which will permit the flexible loop and tie to be moved in a direction opposite the free moving direction.

3. In a device for preforming hair to be curled, a hollow forming rod, flexible means accessible at the back end of the rod for holding the base of a lock of hair to the rod at a point near the head end, and a winder for placing the hair upon the rod.

4. In a device for preforming hair to be curled, a forming rod comprising a body portion, a tip end rotatably mounted within the body portion and partially exposed at its outer end, concaved portions within the tip end formed one in advance of the other and at an angle to the axis of the rod, a handle, and connections between the handle and the tip.

5. In a device for preforming hair to be curled, a forming rod, a winding device mounted thereon, a plurality of spring finger portions extending from the winding device to engage and hold the hair and a spirally formed portion having a spring finger at either end, one of which latter fingers lies in the path of the wound hair and is pressed by the hair to advance the winder.

6. In a device for preforming hair to be curled, a forming rod, a flexible loop, a tie within the rod, a winding device adapted to be movably mounted on the rod, an opening therein for attaching the hair within the winding device, circumferentially disposed spring fingers forming part of the winding device, whereby the hair is held in close contact with the rod during the movement of the winding device.

7. In a device for preforming hair to be curled, a hollow forming rod, a loop of flexible material having both strands passing entirely through the rod and extending as a loop at one end therefrom, and means at the opposite end of the rod for pulling the flexible material further within the rod to tighten the loop.

8. In a device for preforming hair to be curled, a hollow forming rod, a loop of flexible material having both strands passing entirely through the rod and extending as a loop at one end therefrom, and means at the opposite end of the rod for pulling the flexible material further within the rod to tighten the loop including a clamp accessible at that end.

9. In a device for preforming hair to be curled, a forming rod, clamping means for holding the hair near the head and with respect to the forming rod, a winder for the hair spirally surrounding the forming rod and spiralled in a direction to loosen from the forming rod with the winding operation and to tighten upon the forming rod with reverse strain.

10. In a device for preforming hair to be curled, a forming rod, a flexible loop and tie connection for attaching the rod to the hair, a winding device adapted to be movably mounted on the rod and having a spiralled portion terminating in a spring finger adapted to press continuously upon the rod.

11. In a device for preforming hair to be curled, a forming rod, a flexible loop and tie connection for attaching the rod to the hair, a winding device adapted to be movably mounted on the rod and having a spring finger adapted to press continuously upon the rod and means for momentarily relieving the spring pressure of the finger.

12. In a device for preforming hair to be curled, a forming rod and a winder thereon having spiralled engagement with the forming rod adapted to tighten against the forming rod with movement in one direction.

13. In a device for preforming hair to be curled, a forming rod and a hollow winder spirally formed and surrounding the forming rod and having at one end a laterally directed circumferential spring finger adapted to press resiliently toward the rod.

14. In a device for preforming hair to be curled, a forming rod comprising a body portion, a tip having two openings arranged substantially to form a V, a flexible loop passing through the body portion and outward through the V in the tip, and a tie at the opposite end of the body portion uniting the free ends of the flexible loop.

15. In a device for preforming hair to be curled, a forming rod, a winding attachment of spring material spirally wound and adapted to be movably mounted on the forming rod, a spring finger projecting from the body of the winding attachment and pressing against the rod, said finger pressure being released when manual pressure is applied to the body portion of the winding attachment.

16. In a device for preforming hair to be curled, a forming rod, a taper at one end of the forming rod, a winding attachment of spring material encircling the forming rod, movable longitudinally of the forming rod and having a portion thereof in continuous spring contact with the forming rod, at any point throughout the length of the forming rod, and means for relieving the spring pressure upon the forming rod.

17. In a device for preforming hair to be curled, a forming rod, a winding attachment of thin spring material adapted to be mounted thereon, one end of the winding attachment being spirally wound and having a spring finger at the end of the spiral winding, the opposite end being composed of a body portion having a plurality of spring fingers arranged at right angles to the body portion.

18. In a device for preforming hair to be curled, a forming rod, a winding attachment

- of thin spring material adapted to be mounted thereon, one end of the winding attachment being spirally wound and having a spring finger at the end of the spiral winding, the opposite end being composed of a body portion and having a plurality of circumferentially extending spring fingers arranged at right angles to the body portion in one direction and having a hook finger extending from the body portion in a direction opposite the direction of the circumferentially extending spring fingers, and an enlarged opening at the base of the hook finger.
19. In a device for pre-forming hair to be curled, a forming rod, a winding attachment of thin spring material adapted to be mounted thereon, one end of the winding attachment being spirally wound and having a spring finger at the end of the spiral winding, the opposite end being composed of a plurality of circumferentially extending spring fingers arranged at right angles to the body portion in one direction, and having a hook finger extending from the body portion in the opposite direction, an enlarged opening at the base of the hook finger, and a second depressed finger adjoining the plurality of spring fingers.
20. In a device for pre-forming hair to be curled, a forming rod, a winding attachment of spring material having a spirally wound area contacting with the forming rod, and another area surrounding the forming rod in spaced relation thereto.
21. In a device for pre-forming hair to be curled, a forming rod, a winding attachment of spring material having a spirally wound area contacting with the forming rod, and another area surrounding the forming rod in spaced relation thereto, and being composed of a plurality of circumferentially spaced spring fingers of varying lengths, disposed in one direction, and a finger projecting in an opposite direction and in a different space relation.
22. In a device for pre-forming hair to be curled, a forming rod, comprising an exterior nearly cylindrical winding surface, a terminal therefor, a tube connected with the terminal and passing lengthwise within the body of the rod, a loop hair clamp accessible for hair engagement at the terminal and for tightening at the opposite end of the rod, controlled through the tube, a spring clutch between the tube and the body of the rod permitting rotation of the body of the rod with respect to the tube in one direction and checking rotary movement in the opposite direction, and a handle surrounding the tube and engaging the body of the rod to effect rotary movement between them.
23. In a device for pre-forming hair to be curled, a forming rod and a winder operating along the rod having an opening along one side at the end and spring combing fingers

extending circumferentially and inwardly toward the rod in a direction reverse to the intended direction of winding movement whereby the combing fingers tend to comb the hair but ride over tangles in the hair. 70

24. In a device for pre-forming hair to be curled, a forming rod, and a combing device comprising a casing open at one side and having independently resilient combing fingers extending circumferentially and inwardly from the casing in a direction reverse to the direction of winding. 75

25. In a device for pre-forming hair to be curled, a forming rod, a spiral winder surrounding the rod and determining the direction of rotation of the winder and a combing device at the end of the winder comprising a casing open at one side and having independently resilient combing tines extending spirally and inwardly from the casing in a direction reverse to the direction of winding and a guide adjacent the open part of the casing centering the hair with respect to the combing tines. 80
